ISAAC S. ROLAND, OF READING, PENNSYLVANIA.

Letters Patent No. 80,566, dated August 4, 1868.

IMPROVEMENT IN WATER-WHEELS.

The Schedule referred to in these Letters Patent and making part of the same.

TO ALL WHOM IT MAY CONCERN:

Be it known that I, ISAAC S. ROLAND, of Reading, in the county of Berks, and State of Pennsylvania, have invented a new and useful Improvement in Water-Wheels; and I do hereby declare that the following is a full and exact description thereof, reference being had to the accompanying drawings, which form a part of this specification—

Figure 1 being a top view of my improved water-wheel.

Figure 2, a section in the line xx of fig. 1.

Figure 3, a top view of said wheel, with a portion thereof removed, for the purpose of more clearly showing the shape and arrangement of the buckets thereof; and

Figure 4, a side view of an auxiliary portion of the wheel detached therefrom.

Similar letters indicate like parts in all the drawings.

The vertical shaft A of my improved water-wheel may be sustained by means of a suitable step and journal-box, and in any well-known or usual manner.

The portion of the bucket-head or disk B , of my improved water-wheel, which receives the lower edges of the buckets $c c$, is curved downwards, as shown in fig. 2. The upper edges of said series of buckets $c c$ are connected with each other by means of the downwardly-curving rim d , fig. 2. This rim d is not shown in fig. 3, the said omission being for the purpose of more clearly showing the shape and arrangement of its buckets $c c$, and also the arrangement of said buckets with relation to the buckets $f f$ of the water-supplying chute-chamber $f j k l$, which is located within the series of buckets $c c$ of the water-wheel, as shown in fig. 2. This chute-chamber is composed of the upper rim $j k$, the series of chute-buckets $f f$, and the lower rim l . The upper ends of the buckets $f f$ are connected to the inner portion, j , of the upper rim $j k$, and the lower ends of said buckets are connected to the lower rim l , as shown in fig. 3. An annular and upwardly-curving rim, g , which rests upon and is secured to the perforated base-supporter m , receives and supports the chute-chamber $f j k l$ in its proper location within the series of water-wheel buckets $c c$, and in such a manner that the said chute-chamber is allowed to turn freely upon its supporter, and adjust itself to the best position within the water-wheel. The lip k , which radiates from the head of the chute-chamber, and overlaps the inner periphery of the annular supporter g , furnishes the proper means of suspending said chamber in its position within the water-wheel.

When my improved water-wheel is located, as it frequently is, in the bottom of a flume or water-box, the base-supporter m , in fig. 2, represents the position of the bottom of said flume or water-box, and in that case, the upwardly-flaring annular rim g rests on the edge of the opening in the bottom of said flume or box, whilst the water-wheel shaft rests upon a properly-supported step, n , beneath the flume or water-box, as shown in said drawing.

The chute-chamber $f j k l$ not being confined in its position upon and within its supporter g , the action and reaction of the water, as it escapes therefrom and strikes against the series of water-wheel buckets, ordinarily keeps the said chute-chamber in a stationary position; but when any solid obstacle may find its way into the chute-chamber, and be caught between the buckets thereof and the buckets of the water-wheel, the chute-chamber will thereby be made to rotate with the water-wheel, without producing any injury to either, and the wheel will be speedily brought to a stand-still, when the attendant can readily remove said obstruction, and one, perhaps, which, had it been discharged from a stationary chute, would probably have greatly injured or destroyed the wheel.

A tubular gate, h , fits accurately within the chute-chamber $f j k l$, and to opposite sides of said tubular gate, vertical rods $i i$ are secured, which pass upwards, and are connected to any suitable contrivance for raising or depressing said gate, for the purpose of regulating the amount of water that it may be desired to admit to the buckets of the water-wheel.

I do not intend to limit myself to any precise shape or number of the buckets $f f$ in the chute-chamber $f j k l$, nor do I intend to limit myself to any precise shape or number of the buckets in the water-wheel.

Having thus fully described my improved water-wheel, what I claim therein as my invention, and desire to secure by Letters Patent, is—

The movable and self-relieving chute-chamber *f j k l*, located within the series of water-wheel buckets *c c*, and operating therewith, substantially as herein set forth.

I also claim the arrangement of the movable chute-chamber *f j k l*, and its annular supporter *g*, with the disk and buckets of the water-wheel, substantially as herein set forth.

I also claim the combination of the tubular gate *h* with said movable chute-chamber, arranged and operating substantially as herein set forth.

The foregoing specification of my new and useful improvements in water-wheels signed and witnessed, this 10th day of June, 1868.

ISAAC S. ROLAND.
